Primary Examiner — Ania Aman*(74) Attorney, Agent, or Firm* — Leong C. Lei(57) CLAIM

The ornamental design for an electric fireplace, as shown and described.

DESCRIPTION

FIG. 1 is a top and front perspective view of an electric fireplace showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a right side and front perspective view.

The dashed broken lines represent unclaimed portions of the electric fireplace and form no part of the claimed design.
